UNITED STATES PATENT OFFICE.

JOHN HENRY MILLER, OF BALTIMORE, MARYLAND.

BUILDING STRUCTURE.

Application filed May 14, 1921. Serial No. 469,472.

To all whom it may concern:

Be it known that I, JOHN H. MILLER, a citizen of the United States of America, and resident of Baltimore, in the county of Baltimore City and State of Maryland, have invented certain new and useful Improvements in Building Structures, of which the following is a specification.

This invention relates to building structures and particularly to a structure adapted especially for use as a moving picture theater; the said invention having as an object the production of a building of this character with special reference to the orchestra floor, having novel means for seating an increased number of patrons as compared with buildings of this character now known, while at the same time, affording standing room for a large number of patrons approaching the orchestra, and affording furthermore, a view of the screen to those who are standing. By reason of the arrangement just stated, the advantages accruing from the provision for the range of vision of those standing in order that it includes the screen, will permit the patrons who are standing to be amused and, of course, in most instances it will reduce the period of time in which those patrons will occupy the seats, since patrons usually are satisfied to see the exhibition but once, whether they are sitting or standing.

A further object of this invention is to produce an orchestra having an elevated rear portion which may extend rearwardly to any practical degree, and it may extend over store rooms, if on a street, or it may extend over an area occupied by offices, toilets or smoking rooms, or it may extend over an area providing additional lobby space.

It is furthermore an object of this invention to increase the capacity of a theater building of this character without materially adding to the cost of construction, a condition which is accomplished by reason of the fact that the raised portion having the seats has its support of the forward end resting on the orchestra floor, a condition which reduces expenses of construction as compared with those buildings having a suspended gallery structure.

It is a still further object of this invention to produce a structure of the character indicated in which the elevated portion having the seats is accessible in a manner to obviate the obstruction of the view, to any appreciable extent, of those occupying the seats on

the elevated portion of the structure; and it furthermore contemplates the provision of novel means whereby entrances and exits to the orchestra floor are provided in the central part of the lobby in front of the main entrance door.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a plan view of the floor of a theater building embodying the invention;

Figure 2 illustrates a horizontal sectional view below the raised portion of the structure; and

Figure 3 illustrates a longitudinal sectional view taken centrally of the structure.

In these drawings 5 denotes the main orchestra floor of a building in which chambers 6, 7, 8 and 9 are shown at the front of the building on each side of the lobby 10. The chambers 6, 7, 8 and 9 may represent the store rooms heretofore mentioned, or they may represent the additional lobby space, offices, toilets or smoking rooms, it being of course obvious that the uses to which these spaces are put will change under different conditions and localities. The passage-ways 11 and 12 lead to the lobby through any suitable enclosure such as 13 and preferably, a ticket booth 14 is interposed between the passages 11 and 12, so that patrons may purchase tickets and pass to the lobby although, if desired, the passages 11 and 12 may be employed as entrance ways or exit ways, according to the requirements of the management.

The orchestra floor is inclined to the usual pitch which will enable the occupants in the rear seats to look over the heads of those immediately in front of them, and there is also an inclination of the floor of the lobby which will enable those standing to have a better view of the screen. The inclined portion of the lobby is identified by the numeral 15, although it may be found in practice that the arrangement of the inclined portion may be increased or diminished to suit

particular requirements. Preferably, the lobby has an enclosure 16 extending well inwardly and it preferably terminates back of the last row of orchestra chairs. The enclosure 5 may have suitable exits such as 17 and 18, by which the patrons may pass into the orchestra floor in front of the enclosure, or to the elevated extension 19 of the said orchestra floor, the said elevated extension 10 having two of its wings 20 and 21, preferably terminating near the last row of the seats on the orchestra floor, with sufficient room between to form a passage-way for the entrance or exit of the patrons, and a portion 15 of the elevated structure for supporting the seats extends across the lobby from one wing to the other, with sufficient overhead clearance to permit the patrons to pass under it. The wings 20 and 21 are accessible 20 by stairs 22 and 23 leading from the corridor at the sides of the enclosure, and the elevated structure has suitable aisles such as 24 for the passage of patrons, by the use of which, they may reach the different rows of 25 seats on the elevated portion of the structure. Suitable fire escapes 25 may be employed at the rear of the elevated structure, and as they may be of any appropriate type, they are here but conventionally shown.

30 By reason of the fact that the inner ends of the wings are anchored on the orchestra floor, and that the portion of the elevated structure therebetween constitutes a continuation of the wings, a structure strong enough 35 to support a relatively heavy load will be provided in a comparatively simple and inexpensive manner, and with the entrances and exits arranged as indicated, a large number of persons can be accommodated in less 40 time than with present methods of construction.

While I have described this structure as for use particularly for motion picture theaters, it is to be understood that the inventor 45 does not wish to be restricted with respect to such use, and theaters and public halls or

private structures could be built in accordance with this invention, although it has its greatest utility in the production of a hall or auditorium for use in performances 50 or exhibitions.

A distinction must be made between the front of the building and the front of the auditorium or orchestra, since, of course, the front of the building is that part which has 55 the store rooms, whereas the front of the orchestra is toward the screen; hence, the elevated floor is inclined toward the front of the orchestra and away from the front of the structure. 60

I claim:

1. A building structure having a main floor with a lobby at its rear, an elevated structure suitably supported from the main floor adapted to contain seats, the floor of 65 the lobby being inclined to the main floor, the said elevated structure having side wings extending to a point near seats on the main floor, and the said wings being connected by a portion overlying the lobby. 70

2. A building structure having an orchestra floor and a lobby in the rear thereof, compartments on each side of the lobby, an elevated extension of the orchestra floor projecting over the compartments, and the 75 said lobby having an inclined floor leading to the orchestra floor, stairs on each side of the lobby leading to the said elevated portion, and an enclosure having entrance and exit openings located on the inclined floor 80 of the lobby.

3. A building structure having an entrance lobby and compartments for stores on each side of the lobby, an elevated floor structure extending over the lobby and the said compartments, and extending downwardly on an incline, an orchestra floor beyond the lobby, the said orchestra floor and lobby being inclined, and stairs on each side of the lobby 85 from the lobby floor to the front of said elevated portion of the floor. 90

JOHN HENRY MILLER.
